CONTROL FOR TELEMOTORS

Harry W. Link, Merion Station, Pa.

Application February 27, 1947, Serial No. 731,195

10 Claims. (Cl. 60—54.5)

1

My invention relates to remote control apparatus, and more particularly such apparatus wherein a transmitter controls a receiver for responsive movement on either side of a neutral point. The invention is especially useful in connection with telemotors for steering ships, to which use, however, it is not restricted.

One object of the invention is to provide means for positionally synchronizing a transmitter, or control mechanism, and a receiver or operating mechanism, which is governed thereby. A further object is to effect this result without the use of springs or other means which exert different degrees of force in different positions. Other objects and advantages of the invention will be apparent upon consideration of the present specification.

The invention will now be described, by way of illustration, in its application to a telemotor for steering a ship. Thus, in the accompanying drawings—

Figure 1 is an elevation, partly in section and partly in diagrammatic form, showing an apparatus embodying the invention.

Figure 2 is an enlarged elevation of a part of the apparatus shown in Figure 1, as viewed from the right therein, certain parts being broken away or shown in vertical section to illustrate the construction of the apparatus.

Figure 3 is an enlarged view taken on line 3—3, Fig. 2.

Figure 4 is an enlarged view of the switch operating finger shown at the top of Figure 1, and viewed as indicated by the arrows 4—4 in Figure 2; and

Figure 5 shows the solenoid valve illustrated in Figure 1 when in a second position.

In apparatus wherein a control unit governs the action of a remote operating unit, it is important to maintain the two units in synchronized relation. In the past it has been customary to synchronize such units continually by rather complicated arrangements, or to employ for this purpose opposing mechanical forces such as springs. Such synchronizing apparatus does not always give satisfactory results. I have now found that a control unit and a remote controlled operating unit may be automatically synchronized when in neutral position by means of a simple and rugged electrical system which is conveniently responsive to the positional relationships of the transmitter and the receiver when they are not synchronized in their neutral positions.

In the drawings there is shown a control unit

comprising a pair of hydraulic cylinders 10 and 11, wherein plungers 12 and 13, respectively, operate to apply pressure to bodies of liquid contained in the cylinders. The plungers 12 and 13 are actuated simultaneously in opposite directions from the ship's wheel 14, the shaft 15 of which is geared, as by a spur 16 and a gear wheel 17, to a pinion 18 coaxing with racks 19 and 20 which are unitary with or fixed to the upper ends of the plungers 12 and 13 respectively.

Thus, by turning the wheel 14 in the clockwise direction (as viewed in Figure 1) the gear wheel 17 and the pinion 18 are turned counterclockwise, and the plunger 12 is moved downwardly in the cylinder 10. At the same time the plunger 13 is moved upwardly in the cylinder 11. Correspondingly, by turning the wheel 14 counterclockwise (as viewed in Figure 1) the gear wheel 17 and the pinion 18 are oppositely turned, and the plunger 12 is raised, while the plunger 13 is depressed.

It is preferred to make all metal parts of the control unit of brass or bronze, in order not to distort the magnetic field in the neighborhood of the ship's compass.

A conduit 21 connects the inner end (the lower end as viewed in Figure 1) of the cylinder 10 to a synchronizing valve 22, later to be described. A tube 23 extends in continuation of the conduit 21 from the synchronizing valve to an operating unit 24. Similarly a conduit 25 connects the inner end of the cylinder 11 to the synchronizing valve 22, and a tube 26 extends in continuation of the conduit 25 from the synchronizing valve 25 to the operating unit. Thus by moving the plunger 12 downwardly in the cylinder 10 and simultaneously moving the plunger 13 upwardly in the cylinder 11, liquid may be forced from the cylinder 10 into the operating unit and withdrawn from the cylinder 11. Conversely, by moving the plunger 12 upwardly and the plunger 13 downwardly, liquid may be forced from the cylinder 11 into the operating unit and withdrawn from the cylinder 10.

It is preferred to make the conduits 21 and 25, and the tubes 23 and 26 of seamless steel tubing.

The operating unit 24 is of well-known balanced construction. It comprises a cylinder block 27, preferably of steel, having a large-diameter bore 28 extending therein from one side and two equal smaller-diameter bores 29, 29 extending therein from the opposite side, the axis of all bores being parallel. A large-diameter ram 30 is fitted for reciprocation in the large diameter

bore 28, and a pair of smaller-diameter rams 31, 31 are similarly fitted in the bores 29, 29, all rams being suitably packed. The rams are fixed externally of the cylinder block 27 to a rigid frame 32 which is slidably mounted on the cylinder block, all in well-known manner. Thus the rams operate together, the large-diameter ram 30 entering the large-diameter bore 28 as the smaller-diameter rams 31, 31 are withdrawn from the smaller-diameter bores 29, 29, and vice versa. The large-diameter ram, on the one hand, and the combined smaller-diameter rams, on the other hand, are designed to have equal displacement, thus balancing the opposing forces in the operating unit.

A connecting rod 33 ties the rigid frame 32 to the steering power control (not shown). Consequently, when the large-diameter ram moves into the cylinder block 27 and the smaller-diameter rams move out of the cylinder block, the connecting rod is moved away from the cylinder block. Opposite movement of the rams draws the connecting rod 33 toward the cylinder block.

The tube 23, extending in continuation of the conduit 21 from the cylinder 10, enters the inner end of the large-diameter bore through a port 34. Correspondingly the tube 26, extending in continuation of the conduit 25 from the cylinder 11, divides and enters the inner end of each smaller-diameter cylinder 29 through ports 35, 35.

Consequently, the hydraulic system being filled with liquid and with the synchronizing valve open (as shown in Figure 1), turning the ship's wheel 14 in the clockwise direction will effect simultaneous movement of the plunger 12 into the cylinder 10 and the plunger 13 out of the cylinder 11, which in turn will cause pressure to be exerted within the large-diameter bore 28 and relieved within the smaller-diameter bores 29, 29. The large-diameter ram 30 will therefore move out of the cylinder block 27 and the smaller-diameter rams 31, 31 will move into the cylinder block, and the rigid frame 32 will move with the rams to draw the connecting rod 33 toward the cylinder block. Opposite movement of the ship's wheel will obviously reverse the movement of the rams and cause the connecting rod to move away from the cylinder block.

The synchronizing valve 22 is of simple and rugged construction. It comprises a closed cylindrical shell 36 and an axially disposed piston rod 37 therein, which extends out of the shell at one end to terminate in a solenoid core 38. Mounted on the piston rod 37 are three pistons, the outer pistons 39 and 40 being equally spaced from the center piston 41. The outer piston 39, which is nearest the end of the shell through which the piston rod 37 extends, forms an abutment between which and the adjacent end of the shell a spring 42 is compressed. The spring 42 urges the piston rod and pistons toward the opposite end of the shell 36. When the piston rod and pistons are at rest under the action of the spring 42 only, the center piston 41 lies substantially half way between the points at which the conduits 21 and 25 from the control unit are connected into the shell 36. The center piston 41 also lies substantially half way between the points at which the tubes 23 and 26 connecting with the operating unit are connected into the shell. However, such is the design of the synchronizing valve that the distance between the conduit connections is less than the distance between the pistons, whereas the distance between the tube connections is exactly

equal to the center-to-center distance between adjacent pistons.

Consequently, with the synchronizing valve 22 in the position illustrated in Figure 1, flow of liquid between the cylinder 10 and the bore 28 is through a chamber formed in the shell 36 between the outer abutment piston 39 and the center piston 41. At the same time flow of liquid between the cylinder 11 and the bores 29, 29 is through a chamber of substantially equal size formed in the shell 36 between the other outer piston 40 and the center piston 41. All of the operations so far described are effected with the synchronizing valve in this position.

In order to synchronize the transmitter, or control unit, and the receiver, or operating unit, means is provided for short-circuiting the transmitter and simultaneously locking the receiver in neutral position. Thus, in the embodiment of the invention here particularly described, when the receiver or operating unit 24 returns to neutral position and is out of synchronism with the transmitter or control unit, the synchronizing valve is moved into the position illustrated in Figure 5. By shutting off the tubes 23 and 26 the receiver or operating unit is locked in position, since liquid can neither enter nor leave the bores 28 and 29, 29 in the cylinder block 27. At the same time the conduits 21 and 25 are connected through the chamber formed in the shell 36 between the center piston 41 and the outer piston 40. Automatic means is provided for releasing the synchronizing means when said transmitter or control unit has also been brought to neutral position.

Accordingly, certain electric circuits, including mechanically operated switches responsive to moving parts of the apparatus, are connected to a source of direct current indicated by poles 43 and 44. The circuit is connected from the pole 43 to a master switch 45, whence the line connects with a junction point 46.

From the junction point 46 one line connects with a selector switch 47 of the normally-open push button type, thence to a transmitter limit switch 48 also of the normally-open push button type. From the limit switch 48, a wire 49 connects with a receiver limit switch 50. From the receiver limit switch, a wire 51 connects with a solenoid coil 52 which coacts with the solenoid core 38 in which the piston rod 37 of the synchronizing valve terminates. Finally, a wire 53 connects the solenoid coil 52 to the pole 44. With all of the switches in this circuit closed, the solenoid coil 52 will be energized, drawing the core 38 therein against the reaction of the spring 42, and the synchronizing valve will take the position shown in Fig. 5.

A second circuit connects the junction point 46 to a second selector switch 54, which it connects in turn to a second transmitter limit switch 55. Thence a lead 56 completes the circuit to the wire 49. Simultaneous closing of the second selector switch 54, the second transmitter limit switch 55, and the receiver limit switch 50 will energize the solenoid and operate the synchronizing valve 22.

As will be obvious, each circuit contains three switches, all of which must be closed before the synchronizing valve is actuated; and it is to be noted that the receiver or operating unit must be in neutral position before the synchronizing valve can be actuated. Furthermore, all switches are closed by the moving parts of the apparatus.

The contact element of the receiver limit switch

50 is carried by a bell crank lever 57, pivoted as at 58 and having a roller 59 on one arm thereof. The bell crank lever normally is urged by any known or convenient force (here gravity) toward closed-switch position. By this construction, when the receiver or operating unit is in neutral position the roller drops into a depression 60 in the rigid frame 32 of the receiver and the switch is closed. When the receiver moves out of neutral position, the roller 59 rides up out of the depression 60 and the receiver limit switch remains open until neutral position is again attained.

The push button type transmitter limit switches 48 and 55 have rollers 61 and 62, respectively, pivoted at the outer ends of their operating stems. When the transmitter is in neutral position these rollers are in contact with bevel faces 63 and 64 respectively on the outer ends of the racks 19 and 20. Thus, when either rack is elevated the corresponding roller rides along its bevel face and then along its outer surface, thereby closing the adjacent limit switch and maintaining it in closed position. When the rack moves again to neutral position the limit switch opens.

Special means is provided for closing the selector switches 47 and 54. The shaft 65 of the pinion 18 has mounted thereon, by spring-load for frictional actuation thereby, a finger 66, which extends between the actuating rods of the selector switches 47 and 54. Thus, motion of the shaft 65 in one direction will cause the finger 66 to bear against the actuating rod of one switch and close it. Opposite turning of the shaft will cause the finger to close the other selector switch. Frictional mounting of the finger upon the shaft 65 permits the shaft to over-run the position of the finger in which the latter closes a selector switch and to carry the finger over to close the other selector switch as the shaft returns to neutral position. Proper operation of the apparatus is dependent upon this arrangement.

In operation, the synchronizing action is as follows:

Turning the wheel 14 from neutral position in the clockwise direction (Fig. 1) moves the plunger 12 downwardly and the plunger 13 upwardly, thereby drawing the connecting rod 33 toward the cylinder block 27, all in a manner which has already been explained. As the receiver frame 32 moves out of neutral position the roller 59 rides out of the depression in the frame and the receiver limit switch is opened. At the same time the plunger 13 is raised and the rack 20 closes the transmitter limit switch 55. The shaft 65, turning counterclockwise as viewed in Figure 1, carries the finger 66 over to close the selector switch 47 and continues to turn beyond the extreme position of the finger. No current now flows in the circuits at this time.

If the transmitter and the receiver are synchronized, the racks 19 and 20 will return exactly to neutral position and both transmitter limit switches will be open as the wheel 59 drops into the depression in the rigid frame 32 to close the receiver limit switch 59. The solenoid 42 will not be energized, and the synchronizing valve 22 will remain open.

If the transmitter and the receiver are not synchronized, then the receiver will return to neutral position before the transmitter returns to neutral position. The receiver limit switch will therefore be closed while the transmitter limit switch 55 is still held in closed position by the rack 20. Furthermore, because the shaft 65 has

over-run the position of the frictionally-mounted finger, the shaft will carry the finger over to close the selector switch 54 before its pinion moves the rack 20 into position to permit the limit switch to open.

Accordingly, the circuit will be closed from the pole 43 through the master switch 45, through the selector switch 54, through the transmitter limit switch 55, the lead 56, the wire 49 through the receiver limit switch 50, the wire 51 of the solenoid coil 52 and the wire 53 to the pole 44. In consequence, the solenoid will move the synchronizing valve 22 into the position shown in Fig. 5. Thus the receiver will be locked in neutral position while the transmitter will be short-circuited. Further clockwise turning of the wheel 14 will bring the transmitter into neutral position, whereupon the transmitter limit switch will open, breaking the circuit. As a result, the solenoid coil 52 will be de-energized and the synchronizing valve will return to its original position.

Similar action results when the wheel is turned in the counterclockwise direction with respect to Fig. 1.

It is to be noted that the synchronizing action is entirely automatic. It is also to be noted that synchronizing action takes place only when returning to neutral position, and that during synchronization (which is substantially instantaneous) the receiver is locked in neutral position. This is particularly advantageous in steering a ship, since the helmsman never loses rudder control.

At times it may be necessary to synchronize the transmitter and receiver when the receiver is not in neutral position. For example, when fueling a ship at sea it is desirable to maintain the rudder at a small angle while the fueling ship and the fuel ship are lashed together and underway, which may be necessary for as long as twenty-four hours. A slight leak or by-passing in the telemotor system may require constant advance of the helm angle, which may dissipate the entire plunger stroke of the transmitter or control unit.

Emergency means for synchronizing the transmitter and the receiver while the latter is away from neutral position is therefore provided. Thus an emergency switch 67 is provided for locking the receiver in any position while short-circuiting the transmitter. An indicator 68 is also provided whereby the transmitter may be set at the locked setting of the receiver.

As will be at once apparent, closing of the emergency switch 67 will short-circuit the solenoid coil from the junction point 46 through a wire 69, the wire 51 and the wire 53, thereby actuating the synchronizing valve 22 to lock the receiver and short-circuiting the transmitter. Furthermore, the indicator 68 will show the position of the transmitter, which when short-circuited may be moved to a setting corresponding to that at which the receiver is locked.

The indicator here illustrated comprises a needle 70 pivoted to move over a scale 71 adjacent the wheel 14. The needle is carried by a stem 72 fixed to a bevel wheel 73 in mesh with a second bevel wheel 74 which is driven through gear segment 75 from the pinion 18. The gearing is such that when the transmitter and receiver are synchronized the needle always indicates the rudder angle on the scale.

Accordingly, to synchronize the transmitter and receiver when the latter is not in the neutral position, the emergency switch is closed, thus

locking the receiver and short-circuiting the transmitter, and the position of the transmitter is adjusted until the indicator indicates that the transmitter is in position corresponding to the locked position of the receiver. The emergency switch is then opened. The emergency switch is kept open during all normal operations.

Adjacent the wheel shown in Figure 2 is shown a conventional steering connection 76 to a flying bridge above the wheel house. A clutch 77 is indicated whereby the connection may be used or disconnected.

From the foregoing, it will be apparent that simple, rugged and automatic means have been provided for synchronizing a transmitter or control unit and a remotely controlled receiver or operating unit. Furthermore, manually actuated synchronization is provided for use in unusual circumstances.

The form of the invention herein described and illustrated in the accompanying drawings is presented merely to indicate how the invention may be employed. Other forms and applications of the invention will suggest themselves to those familiar with remote control apparatus.

I claim:

1. Remote control apparatus comprising a hydraulically operated receiver and a hydraulic transmitter for operating said receiver in combination with synchronizing apparatus for said transmitter and receiver, said synchronizing apparatus comprising means to hydraulically disconnect said transmitter and receiver and simultaneously to hydraulically lock the latter in a predetermined position, automatic means to operate said disconnecting and locking means only when said receiver is in said predetermined position including control means operated by said transmitter, and other control means operated by said receiver only in said predetermined position thereof.

2. Remote control apparatus comprising a hydraulically operated receiver and a hydraulic transmitter for operating said receiver in combination with synchronizing apparatus for said transmitter and receiver, said synchronizing apparatus comprising means to hydraulically disconnect said transmitter and receiver and simultaneously to hydraulically lock the latter in a predetermined position, automatic means to operate said disconnecting and locking means only when said receiver is in said predetermined position including control means operated by said transmitter and control means operated by said receiver only in said predetermined position thereof, and other control means actuated by said transmitter alone for rendering said automatic means ineffective to operate said disconnecting and locking means.

3. Remote control apparatus comprising a hydraulic control unit, a hydraulic operating unit actuated by said control unit, means for synchronizing the operation of said units comprising a synchronizing valve to hydraulically disconnect said control unit and operating unit and simultaneously to hydraulically lock the latter in a predetermined position, and electrical means automatically actuated by said control unit for operating said synchronizing valve only when said operating unit is in neutral position including control means actuatable by said operating unit in said predetermined position only of the latter.

4. Remote control apparatus comprising a hydraulic control unit, a hydraulic operating unit actuated by said control unit, means for

synchronizing the operation of said units comprising a synchronizing valve to hydraulically disconnect said control unit and operating unit and simultaneously hydraulically lock the latter in a predetermined position, electrical means for operating said synchronizing valve only when the operating unit is in said predetermined position including control means actuatable by said control unit, and other control means actuatable by said operating unit in said predetermined position only of the latter.

5. Remote control apparatus comprising a hydraulic control unit, and a hydraulic operating unit actuated by said control unit, in combination with a solenoid-type synchronizing valve for hydraulically disconnecting said control unit and simultaneously hydraulically trapping said operating unit, and electrical means automatically actuated by said control unit operatively connected to the coil of said solenoid-type valve for operating said valve.

6. Remote control apparatus for steering a ship comprising a hydraulic control unit operated by the ship's wheel, a hydraulic operating unit operatively tied to the steering power control of the ship, and hydraulic connections between said units, in combination with means for synchronizing said units comprising a synchronizing piston valve connected across said hydraulic connections for disconnecting said control unit from said operating unit and simultaneously hydraulically locking said operating unit in a predetermined position, a solenoid having its core connected to the piston rod of said valve, an electrical circuit operatively connected to the coil of said solenoid, and switches operated by moving parts of said control unit and said operating unit for making and breaking said electrical circuit to operate said solenoid.

7. Remote control apparatus for steering a ship comprising a hydraulic control unit operated by the ship's wheel, a hydraulic operating unit operatively tied to the steering power control of the ship, and hydraulic connections between said units, in combination with means for synchronizing said units comprising a synchronizing piston valve connected across said hydraulic connections for disconnecting said control unit from said operating unit and simultaneously hydraulically locking said operating unit in a predetermined position, a solenoid having its core connected to the piston rod of said valve, an electrical circuit operatively connected to the coil of said solenoid, a switch constructed and arranged to be closed by said operating unit at neutral rudder position, and a switch responsive to a moving part of said control unit for closing said circuit to operate said solenoid.

8. Remote control apparatus for steering a ship comprising a hydraulic control unit operated by the ship's wheel, a hydraulic operating unit operatively tied to the steering power control of the ship, and hydraulic connections between said units, in combination with means for synchronizing said units comprising a synchronizing piston valve connected across said hydraulic connections for disconnecting said control unit from said operating unit and simultaneously hydraulically locking said operating unit in a predetermined position, a solenoid having its core connected to the piston rod of said valve, an electrical circuit operatively connected to the coil of said solenoid, a switch constructed and arranged to be closed by said operating unit at neutral rudder position, a switch responsive

to a moving part of said control unit for closing said circuit to operate said solenoid, and an emergency switch connected in parallel in said circuit for independently energizing said solenoid to close said valve, substantially as described.

9. Remote control apparatus for steering a ship comprising a hydraulic control unit operated by the ship's wheel, a synchronizing valve, a hydraulic operating unit operatively tied to the steering power control of the ship, two conduits connecting said control unit with said synchronizing valve, two tubes connecting said valve with said operating unit, said tube connections being spaced more widely than said conduit connections in said valve, a piston rod in said valve, pistons carried by said piston rod and spaced equally with the spacing of said tubes in said valve, and a spring operatively connected with said piston rod for yieldably maintaining one piston between the two conduit connections in said valve and between the two tube connections in said valve, in combination with a solenoid for moving said piston rod against the action of said spring to close the tube connections with said pistons and to short circuit the conduit connections between said pistons, and an electrical circuit connected to said solenoid for closing said valve.

10. Remote control apparatus comprising a control unit, an operating unit connected to said control unit for actuation thereby, a synchronizing unit connected between said control unit

and said operating unit, a solenoid operatively connected to said synchronizing unit, and an electrical circuit connected in series with said solenoid, in combination with an operating unit

5 limit switch connected in said circuit in series with said solenoid, mechanical means governed by said operating unit for closing said limit switch when said unit is in neutral position, a normally-open control unit limit switch in said circuit in series with said first-named switch positioned to be closed by an element of said control unit when said unit is out of neutral position, a selector switch in series with said limit switches in said circuit, and a frictionally operated finger for closing said selector switch only when said control unit is returning to neutral position, whereby said synchronizing unit is operated only when said limiting switches and said selector switch are all closed.
